OF OHIO.

DOOR AND HINGE CONSTRUCTION.

1,416,812.

Specification of Letters Patent. Patented May 23, 1922.

Application filed August 18, 1919. Serial No. 318,229.

To all whom it may concern:

Be it known that we, JOSEPH FREYBERG and LEO F. WUBBOLDING, citizens, respectively, of Austria and of the United States, and residents of Newport, in the county of Campbell and State of Kentucky, have invented certain new and useful Improvements in Door and Hinge Constructions, of which the following is a specification.

10 Our invention relates to metal safes and the like; and its object is to simplify the construction of such devices and make them more secure and substantial.

Our invention consists in the combination 15 of parts and in the details and construction and arrangement of parts as will hereinafter be more fully described and claimed.

In the drawings:

Fig. 1 is a sectional plan view of part of 20 a safety-deposit cabinet embodying our invention;

Fig. 2 is a partial front elevation of the same;

Fig. 3 is a detail perspective view of the 25 upper hinge corner of one of the doors with a single hinge therein;

Fig. 4 is a similar view of the same before the hinge is placed therein;

Fig. 5 is a detail perspective view of a 30 single hinge;

Figs. 6 and 7 are detail perspective views of meeting hinges;

Fig. 8 is a view similar to Fig. 5 showing a modified single hinge;

35 Fig. 9 is a partial plan view of the hinge end of a door with this modified hinge fixed therein;

Fig. 10 is a vertical longitudinal section on a plane corresponding to the line 10—10 40 of Fig. 9;

Fig. 11 is a view similar to Figs. 5 and 8 showing another modification of the single hinge; and

Fig. 12 is a view similar to Fig. 9 showing 45 this other modified hinge fixed in a door.

This door and hinge construction is especially designed for safety-deposit cabinets and it is in such a construction that it is exemplified herein; although it will 50 be understood that our invention is applicable to the construction of other similar devices where its advantages will be realized.

These safety-deposit cabinets are preferably constructed as disclosed and claimed in

our co-pending application, Serial No. 55 316,229, filed August 8, 1919. Among other details which are fully shown in said co-pending application such a construction comprises the horizontal partitions or shelves 1 and the upright partitions 2 which latter 60 do not extend entirely to the fronts of the shelves 1 but are continuous up and down through slots in said shelves 1. These partitions 2 have their front ends received by jambs 3 or 3' each of which also is continuous 65 thorough slots in the shelves and set back from the front edges of the shelves so that the metal of the shelves is continuous past the front edges of these jambs.

The doors 4 fit snugly in the spaces between the shelves 1 and the jambs 3; each consisting of a heavy metal plate with its upper and lower edges substantially horizontal and the front or free edge 5 somewhat beveled inwardly to pass the jamb. The 70 rear or hinged edge has the tongue 6 running from top to bottom of the door adjacent to the inner or rear surface of the door.

Some of the doors swing from left to right 80 as the two doors shown at the left in Figs. 1 and 2; but other doors such as the one at the right in these figures swing from right to left. These latter doors are provided in a cabinet which is to have its right side 85 against a wall or the like which would prevent the door from swinging entirely open if it were hinged to swing from left to right. It will be understood that other arrangements may be made; all the doors 90 swinging the same way if there is no need for any of them swinging otherwise. But where this is provided for there is some difference both in the jambs and in the hinges because this involves the bringing of the 95 hinged ends of right-hand and left-hand doors adjacent.

Where the hinged end of one door is adjacent to the locking end of the next door as at the left in Figs. 1 and 2, the jamb 3 is 100 made with a shoulder 7 behind which the tongue 6 enters; and the other side of the jamb 3 has the strike 8 against which the free end of the other door abuts and behind which engages the bolt 9 of the lock of that 105 door. Where the hinged ends of two doors are adjacent, as at the right in Figs. 1 and 2, the jamb 3' has the grooves 7' on oppo-

site sides to receive the tongues 6 of the two doors. For these left-hand-swinging doors a suitable strike is provided which, together with other details, which are fully shown 5 in the aforesaid co-pending application, are omitted herefrom. Enough of their construction has been described to elucidate the present invention. It is sufficient to say that the jambs 3 and 3', which are not only set 10 back from the front edges of the shelves 1 but which are fitted in the correspondingly shaped slots in the shelves, are very secure against removal forwardly.

It greatly conduces to the simplicity of 15 construction of this kind of cabinet to hinge the doors in those parts of the shelves 1 immediately in front of the partitions 2 and the jambs 3 or 3'. It is to hinges suitable for this that our present invention is especially directed.

Each one of the hinges 10 extends out 20 from the face of the door and over in front of the jamb 3 where it has its upright pivot pin 11. The hinges of doors of succeeding 25 horizontal series are in vertical alinement so that a single hinge pin 11 extending through a hole 12 in the shelf 1 serves for the hinges 10 both above and below the respective shelf as clearly shown in Fig. 2. 30 The hinges 10 are of full depth throughout their length; but when hinged ends of doors are adjacent the hinges 10' are made with their pivot-pin-receiving parts only half the height of the hinge and meeting hinges are 35 inversely arranged so that the two half parts are in vertical alinement with the pin through them. It will be understood that in either case the hinge pin 11 is fixed to only one of the hinges so as to allow the 40 other one or anyone of the other three doors to swing independently of the door in the hinge of which the pin is fixed.

According to our present invention the upper and lower edges of the door 4 near its 45 rear or hinged end have slots 13 cut in them extending diagonally in from the front of the door to cylindrical sockets 14 wider than the slots. The hinge 10 or 10' is made with its middle part or shank 15 just wide enough 50 to fit tightly in the slot 13 and having on its end the cylindrical part or head 16 that fits tightly in the socket 14. The slot 13 and socket 14 are of just the right depth that when the hinge 10 or 10' is driven into them 55 the upper or lower edge of the hinge will come flush with the top or bottom edge of the door as may be the case. The pivot-pin-receiving part 17 of the hinge 10 of the full height of the hinge or the part 17' of the 60 hinge 10' of half the height is of substantially the same diameter as the cylindrical head 16; but preferably while the shank 15 meets the head 16 radially so as to leave vertical shoulders at each side it meets the part 65 17 at a tangent. This formation with the

proper arrangement results in throwing the shank 15 of the hinge away from the jamb 3 or 3' to afford ample clearance when the door closes. It will be understood that these hinges are thus set in the doors at the proper 70 angle to bring their pivot-receiving parts 17 or 17' in vertical alinement with the pivot openings 12 in the shelves 1 when the doors are closed. These hinges 10 or 10' are preferably driven into the door slots 13 and 75 sockets 14 under very heavy pressure so that they are as substantial as if formed integral with the door.

The hinges 10 and 10' shown in Figs. 1 to 7, inclusive, are of solid formation; the 80 preferred method of making them being to roll a bar of the proper cross-section and then cut this bar into short lengths each of which will be one of the hinges after boring the hinge pin opening in the part 17; or in 85 the case of the hinge 10' the cutting away half of the part 17' and providing the hinge pin opening therein.

In the modification shown in Figs. 8 and 9, the hinge 10' is of the same general 90 formation but is made of a long rectangular sheet of material bent upon itself with its ends meeting to form the rear part of the hinge 16'' and suitably formed intermediate of these ends and the junction of the two 95 folded-together members and the front side of the hinge-pin-receiving part 17'' to constitute the shank 15''. In this shank the two members of the sheet lie against each other; but in the head 16'' and the part 17'' 100 they are bent around so that each has a vertical opening down through it. The opening of the part 17'' receives the hinge pin. The vertical opening in the head 16'' receives a pin 18 which is driven tightly 105 therein after this head 16'' and shank 15'' have been inserted into the socket 14 and slot 13 of the door. Driving this pin 18 tightly herein firmly wedges the two halves of this head 16'' against the sides of the 110 socket 14 and thus very tightly fixes the hinge 10'' in the door. It will be understood that all of the parts are very accurately formed so that this wedging effect causes only an imperceptible movement of the 115 parts. Also it will be understood that this sheet metal hinge may have half of its pivot-pin-receiving part 17 cut away to correspond to the meeting hinges shown in Figs. 6 and 7 and thus be used in the same 120 way that they are, as was just fully described.

In the further modification of Figs. 11 and 12 the hinge 10''' is made of sheet metal as in the example just described; the most 125 important difference being that the shank 15''' not only joins the pivot-pin-receiving part 17''' at a tangent but joins the head 16''' in the same way. Such a formation is somewhat simpler and may be found more 130

suited to the making of the hinges of sheet metal since there are not so many bends in the metal.

It has been stated that these hinges are 5 very tightly driven into the doors. But it will be understood that in conjunction with the shelf and partition structure that has been described and which is the subject matter of the co-pending application mentioned, 10 it is practically impossible to remove the hinges from the doors when the doors are closed; because the upper or lower edges of the hinges are closely abutted by the shelves 1 above and below, respectively. A loosely 15 fitted hinge could be removed somewhat more readily when the door is open; but a thief would have no need to remove a hinge if the door were open. Also when these or any similar hinges are used in conjunction 20 with the tongue 6 entering behind a part of the jamb 3 or 3' the security of closure does not depend upon the security of the hinge. This permits the hinge to be made of any 25 material that will have the proper strength and wearing qualities to adapt it only as a hinge for the door to swing upon. Usually the door is made of steel and the hinges are brass or bronze.

It will be understood, however, that we 30 are not limited to any certain material or proportions nor even to those details of the partition or shelf construction just alluded to. The hinge as variously exemplified herein or in any other modifications adapting 35 it to somewhat different uses or for use with different other details of construction is suitable for devices other than safety-deposit constructions and the like. Therefore, while certain constructional details are deemed 40 preferable in connection with our invention, and we have shown and described these rather specifically in elucidating the construction and use of our invention, as is required, we do not wish to be understood as 45 being limited to such precise showing and

description, but having thus fully described our invention, what we claim as new and desire to secure by Letters Patent is:

1. In a door and hinge construction, a door, and a hinge member embedded in said door near one end thereof and projecting outside the face of said door and over past said end. 50

2. In a door and hinge construction, a door having a socket in its edge near one end thereof and having a slot leading from said socket out through the face of said door and over toward said end, and a hinge member comprising a head fitting in said socket and a shank fitting in said slot and 60 projecting out therefrom and over past said end. 55

3. In a door and hinge construction, a door having an opening in its edge near one of its ends, and a hinge member inserted 65 into said opening through said edge and projecting outside the face of said door and over past said end, the depth of said opening and the height of said hinge member being substantially equal, whereby the top of said 70 hinge member lies substantially flush with said edge of said door.

4. In a door and hinge construction, a door having a socket in its edge near one end thereof and having a slot leading from said 75 socket out through the side of said door and over toward said end, and a hinge member comprising a head fitting in said socket and a shank fitting in said slot and projecting out therefrom and over past said end, and comprising a hinge-pin-receiving part at its outer end, said shank joining said head substantially radially thereto but joining said hinge-pin-receiving part substantially at a tangent thereto for the purposes set forth. 80 85
